UNITED STATES PATENT OFFICE.

ALFRED E. LATHAM, OF BROOKLYN, NEW YORK.

ELECTRICAL CONNECTER.

Application filed November 10, 1921. Serial No. 514,231.

To all whom it may concern:

Be it known that I, ALFRED E. LATHAM, a citizen of the United States, and a resident of the city of New York, borough of Brooklyn, in the county of Kings and State of New York, have invented a new and Improved Electrical Connecter, of which the following is a full, clear, and exact description.

This invention relates to an electrical connecter, and has for an object the provision of means whereby a circuit wire may be simply but very securely fastened within the connecter so that it will stand greater strains and will make a much more efficient electrical contact.

Another object resides in the particular construction and arrangement of parts which are hereinafter described and claimed and shown in the accompanying drawings.

20 The invention is illustrated in the drawings, of which—

Figure 1 is a longitudinal section taken through the connection.

Fig. 2 is a side elevation showing the two 25 parts of the connecter spaced apart.

Fig. 3 is an end view of the plug portion of the connecter.

The drawings illustrate a preferred form 30 of my invention but it is understood that modifications in the arrangement and construction of the parts may be adopted without departing from the general spirit of the invention as set forth hereinafter.

This invention as shown in the drawings 35 comprises a socket portion A and a plug portion B. The socket portion comprises a shell 1 of any suitable insulating material, such as ebonite, having disposed in a suitable portion therewithin a metallic socket body portion 2. This socket is provided 40 with a bore 3 threaded as at 4 along its outer edges and provided with a curved shoulder 5 at an intermediate portion. This bore 3 is reduced toward the inner end, as at 6, and 45 is provided with a shoulder 7, and beyond this is still further reduced as a small bore 8. Midway of the body portion of the socket 2 are bayonet pins 9 and 10 which extend in opposite directions therefrom through the 50 ebonite shell 1 to form means for fastening the connecter to any suitable co-operating member. A contact pin 11 extends through the aperture or bore 8 and has a flange 12 thereon engaging the shoulder 7. 55 This flange is backed by a spring 13, the

other end of which bears against wires 14. These wires pass through a bore 15 in a metal plug portion 16 and are bent around over the end thereof to be gripped between the projecting portion 17 of the plug and the 60 walls of the socket and to bear against the curved shoulder 5 previously mentioned. The projecting plug portion 17 is provided with threads to engage in the threaded bore 4.

The plug member is provided, likewise, with an insulating body portion 18 provided with a knurled ring flange 19 and at its front end with a depressed recess 20 into which the end of the shell 1 extends as the plug portion 16 is screwed into the socket portion 2. The plug portion 16 and the insulating body portion 18 are provided with aligning apertures forming the bore 21 through which the conductor 22 extends. The end of the conductor is stripped so that the wires may 70 pass through the bore 15 with their ends bent over and contacting along the outer surface of the projecting portion 17.

In the operation of the device, after the 75 wires have been thus bent over the end 17 of the plug, the plug portion 16 is screwed into the socket 2, forcing the wires against the side and curved portions of the walls of the socket 2 to form a very firm, strong and intimate contact therebetween and also to compress the spring 13 so as to hold the pin 11 outwardly. As the flange 19 with the recess 20 embraces the end of the shell 1, the 80 joint between the body portion 18 and the socket 2 is very perfectly insulated by the 85 engagement of the insulating shell.

In this manner I have provided a simple, efficient connecter device that can be readily disassembled, and when assembled forms a 90 compact structure in which the wires are 95 very firmly and strongly gripped.

What I claim is:

1. An electrical connecter which comprises 100 a conducting socket portion, a sleeve of insulating material surrounding the same, said socket portion having an interior bore threaded at one end, a plug portion of conducting material, a sleeve of insulating material therearound, said last mentioned sleeve on the face adjacent the socket portion having a recess into which the end of the first-mentioned sleeve extends, said plug having a projecting head to extend into the bore of the socket portion and threaded along a portion of said head to engage with the threads 105 110

in the bore of the socket whereby the socket member and the plug member are tightly engaged.

2. An electrical connector which comprises
5 a conducting socket portion, a sleeve of insulating material surrounding the same, said socket portion having an interior bore threaded at one end, a plug portion of conducting material, a sleeve of insulating material therearound, said last mentioned sleeve on the face adjacent the socket portion having a recess into which the end of the first-mentioned sleeve extends, said plug having a

projecting head to extend into the bore of the socket portion and threaded along a portion of said head to engage with the threads in the bore of the socket whereby the socket member and the plug member are tightly engaged, said extending head portion having a bore therethrough, and conducting wires extending through said bore and beyond the end of the head, said wires being bent backwards along the outside surface of the head to be gripped between the walls of the socket and the head. 15 20

ALFRED E. LATHAM.
